Patented Nov. 3, 1914.

UNITED STATES PATENT OFFICE.

EDGAR W. ALLEN, OF SAN JOSE, CALIFORNIA.

COIN-CONTROLLED LOCKING MECHANISM.

1,116,198.

Specification of Letters Patent.

Patented Nov. 3, 1914.

Application filed March 11, 1913. Serial No. 753,540.

To all whom it may concern:

Be it known that I, EDGAR W. ALLEN, a citizen of the United States, residing at San Jose, Santa Clara county, California, have 5 invented new and useful Improvements in Coin-Controlled Locking Mechanism, (see Patent No. 988,059, issued to me, EDGAR W. ALLEN, March 28, 1911,) of which the following is a specification.

10 This invention relates to a coin controlled lock which may be made of any suitable materials best suited to the construction to which it is to be attached.

My further object is to provide a simple 15 and durable automatic locking device which may be constructed to admit a coin of any dimension, by which it can be controlled, the coin or piece of metal acting as a key to disengage the locking lever from the bar 20 locked.

This invention consists in the combination of parts more fully described by reference to the accompanying drawings in which—

25 Figure 1 is a front view showing position of the levers and bars when locked, also position of the coin ready to contact the locking lever. Fig. 2 is an upright section of each member of the lock, showing the bars 30 A—A to be locked. Fig. 3 shows a cross-section of the coin carrier and race at B—B, Fig. 1 in combination with the casing C—C. Fig. 4 shows a section of the bars, locking lever 2 and spring latch 4, and contacting 35 bar 9' as held in the slot D Fig. 1.

In the drawings C—C indicates the casing which is slotted at D to receive the bars to be locked.

The locking lever 2 is held by a pivot 3 40 Fig. 1, which is set in a boss raised to any desired height in the casing C. The governor or latch lever 4 Fig. 1, is also held on the pivot 5 which is set in a boss the same as the locking lever 2. To the latch lever 45 4 is attached two tongue steel springs 6 and 7 secured by two screws 5', these two springs are held under tension by the latch lever 4 which is forced into position by the contacting bar 9' which may be applied by 50 any means whatever, and retained until freed by the action of a coin on the locking lever 2. The spring 7 acts against the end of the coin carrier 8 Fig. 3 and is so adjusted that it will return the carrier 8 to 55 its normal position as shown at B—B Fig. 1 and will allow free action of the coin car-

rier 8 without moving the locking lever 2 when (the key) a coin 10 is not in place.

The coin carrier 8 is so constructed that when a coin 10 is in place (as shown at B—B) it can be pushed forward by the finger at E and so engage the coin 10 between the shoulder 15 in the coin carrier 8 and the locking lever 2 Fig. 3, until the locking lever 2 is forced into the position shown by dotted lines 2' when the contacting bar 9' can be thrown out of the slot D by any force in use when all levers will be free and the coin will drop through an opening 10' into the receptacle 11.

The locking lever 2 is weighted at 2'' sufficient to normally retain the latch lever 4 in the position shown by dotted line 4'' Fig. 1, ready for the attack by a bar 9' to be locked which automatically forces the locking levers into position to receive and hold the coin. I provide a race 12 Fig. 1 to guide the coin 10 into the carrier 8, the coin to be inserted in slot 15' Fig. 2 and held in place by an auxiliary cover 14 Fig. 3 which extends across the face at B—B and upward covering the race 12. The coin carrier 8 is encircled and held in position and guided by an extra boss 16 Fig. 2 set through the casing C and retained by a screw 17, Fig. 1. 85

Having thus described my invention, what I claim and desire to secure by Letters Patent is:

1. In a coin-controlled mechanism in combination with an element to be locked, a reciprocal coin carrier having a coin-receiving recess on one face thereof, a locking lever to lock said element having its lower end extending into said recess so as to close the outer end of the latter, a latch lever pivoted to one side of said locking lever, and a pair of independently acting flat springs connected to said latch lever, said springs being of varying lengths, the longer spring extending below the shorter spring and being engaged at its lower end with the inner end of the coin carrier, and the shorter spring having its lower end extending in spaced relation to the front face of the longer spring and engaged with the rear face of the latch lever, said latch lever being moved to a position where its said springs tension the coin carrier and the locking lever by the movement of said element to locking position.

2. In a coin-controlled mechanism in combination with an element to be locked, a

reciprocal coin-carrier having a coin receiving slot, a locking lever to lock said element having a part extending into said slot, a latch lever, and a pair of independently acting spring elements connected to said latch lever one of which elements engages the coin carrier and the other of which elements engages the locking lever, said latch lever being moved to a position where its said 10 springs tension the coin carrier and the locking lever by the movement of said element to locking position.

3. In a coin-controlled mechanism, a reciprocal coin-carrier, locking means having 15 a part which is disposed adjacent to the coin-carrier so as to provide a space between

the coin-carrier and said part of the locking means so as to allow a coin to be placed in said space, an element which is locked by said locking means, and movable means 20 having a pair of independently acting spring devices one of which tensions the locking means and the other of which tensions the coin-carrier, said movable means being moved to a position where its said devices tension the coin-carrier and the locking means by the movement of the element to locking position.

EDGAR W. ALLEN.
